SPIRAL COIL LOOSE-LEAF BINDER
AND THE LIKE

Herman Busse, Brooklyn, N. Y., assignor to Milton C. Johnson Co., New York, N. Y., a corporation of New York

Application July 22, 1952, Serial No. 300,189

4 Claims. (Cl. 281—19)

1

This invention relates to bookbindings of the so-called "spiral" type, wherein a plurality of leaves is maintained together by a helical or spiral coil. It is an object of the invention to provide improved means by which such a coil can be effectively secured in place within the book covering.

It is another object of the invention to provide an improved bookbinding, having its parts arranged for quick and simple assemblage by the purchaser or user, so that the article can be delivered in flattened, "knock-down" or dis-assembled condition to not only facilitate shipping but to result in a saving of assembling cost to the manufacturer.

It is another object of the invention to provide a bookbinding of this character in which the parts may be readily fabricated from sheet metal, which parts can be easily fitted together in assembled relationship by the purchaser or user, and when assembled, the binding will be strong and sturdy and effectively hold the leaves of the book in proper relationship.

It is still another object of the invention to provide an improved assembly method for parts of a bookbinding, enabling said parts to be assembled in operative relationship with a minimum of effort and by the use of a simple hand tool to provide a book binding of strength and satisfaction.

In the accompanying drawings, wherein an illustrative embodiment of the invention is disclosed, Fig. 1 is a perspective view of the bookbinding, showing the leaves and the spiral which connects the same separated from the mounting means;

Fig. 2 is a perspective view of the base plate, the mounting strip and the end plates which, when assembled, provide the mounting means for the leaf-carrying spiral;

Fig. 3 is a longitudinal sectional view through the back or binding of the book, showing the base plate secured thereto;

Fig. 4 is a sectional view, taken substantially on the line 4—4 of Fig. 1, looking in the direction of the arrows; and

Fig. 5 is a sectional view, taken substantially on the line 5—5 of Fig. 4, looking in the direction of the arrows.

Referring to the drawings, 1 and 2 indicate the respective covers of a book to which the improved binding is applied. The covers 1 and 2 may be of conventional form and are connected by the curved back panel 3, which may consist of an outer covering 4 of cloth, and an inner lining strip 5, also of cloth, with a suitable reinforcing or stiffening material, such as cardboard 6, interposed between the outer covering and lining strip.

Located under and concealed by the lining strip 5 is a stiff backing plate 7 preferably of thin metal. This strip in its initial form, is flat as

seen in Fig. 2 and is inserted in the back of the book under the lining 5 in such flat form. Subsequently, it is transversely curved, as clearly seen in Fig. 5. The backing strip 7 is formed with two stamped-out tongues 8 located adjacent to the opposite ends of the strip. Normally these tongues lie down flatly, as shown in Fig. 3, projecting just sufficiently to enable them to be engaged and bent upwardly. These tongues are exposed on the outside of the lining strip 5 so that they may be engaged with the spiral-engaging member or mounting strip 10 to be described, as well as with end members 11.

The spiral-engaging member or mounting strip 10, shown most clearly in Fig. 2, is an elongated metallic strip having its opposite ends turned or bent into hook-shaped formation as indicated at 12 and 13. The mounting strip 10 is also provided adjacent to these hook-shaped ends with apertures or slots 14 of a shape and size to permit of the passage of the tongues 8 through them. The mounting strip 10 is also slit inwardly from its opposite longitudinal edges 15 and 16 to provide a plurality of upstanding, spaced lugs 17 and 18 which fit between the convolutions of the spiral binding 28 to hold the same in the required spaced relationship and prevent endwise or longitudinal compression of the spiral binding member.

30 The end members 11 for the binding each consists of a disk-shaped end wall 19 from which an integral channel-shaped strip 20 extends at substantially right angles. This channel-shaped strip 20 is of a width to enable the end portions 35 of the spiral-retaining strip 10 to be received within it, with said end portions of the strip 10 being embraced between the side walls 21 and 22 of the channel strip. Provided in the bottom of the channel strip 20 is a slot or aperture 23 of a 40 shape and size to permit of the passage of one of the tongues 8 through it.

The spiral or helix 28 is of the conventional wire type and receives and holds the leaves 24 in the conventional manner.

45 When the book is delivered, it may be in disassembled condition but ready for quick and simple assembly by the recipient. The book may be delivered with the base plate 7 secured in place in the back of the book but in its flattened form, thereby permitting the shipment of the book covers in perfectly flat condition. While the book covers are flat, the tongues thereof are bent downwardly as shown in Fig. 3. The first step in the assembly of the book consists in curving the back of the book and plate 7 transversely and then elevating the tongues 8 to the vertical position as shown in Fig. 2. The curving of the plate can be done by a press and raising of the tongues can be done by the insertion of a knife blade or other simple tool under each tongue and bending the tongue upwardly to vertical position.

When the tongues 8 have been so raised, the spiral-retaining strip 10 then has the end members 11 fitted on its opposite ends, the channel strip 20 being slipped under the end of the strip 10 until the apertures 23 in the channel strips 20 are in alignment with the slots 14 in the strip 10. Now, the strip 10, with the end members 11 fitted in place as just described, is placed in the back of the book in position to cause the tongues 8 to project upwardly through the aligned apertures 14 and 23. When the parts have been positioned as above described, the tongues 8 are then bent over or clenched as clearly seen in Fig. 1 and they will then serve to attach the mounting strip 10 as well as both of the end members 11 to the base plate 7 which was previously secured in the back of the book between the outer fabric 4 and inner fabric 5. All that now remains to complete the assembly of the binding is to connect the spiral or helix 28 to the mounting strip 10 and this is done by inserting the inturned hooks 12 and 13 within a few of the convolutions of the spiral at its opposite ends to thereby engage the hooks with such convolutions, as clearly shown in Fig. 4 and confine the spiral or helix between 25 the end plates 19 of the two end members 11.

The lugs 17, extending upwardly from the mounting strip 10 will enter between the convolutions of the spiral 28 and will hold the same in properly spaced relationship and prevent end- 30 wise shifting or compacting of the helix.

Since the several parts of the binding, namely, the base plate 7, the mounting strip 10 and the end-members 11 are held together solely by the engagement with the tongues 8, formed as integral parts of the base strip 7, it will be apparent that the assembly of these parts into a sturdy binding structure is easy, and may be effected without special tools or skill. Hence, the book 40 and its component parts may be sold or delivered with its parts in separated relationship if desired, leaving the assemblage to the purchaser or user of the book. On the other hand, if it is desired to deliver the book in fully assembled condition, this can be readily done without requiring any 45 substantial manufacturing expense since the assembling time required is short indeed.

Having described one embodiment of the invention, it is obvious that the same is not to be restricted thereto, but is broad enough to cover 50 all structures coming within the scope of the annexed claims.

What I claim is:

1. A book binding comprising a pair of covers connected by a back strip, a base plate overlying and secured to said back strip, tongues struck from the base plate, a mounting strip lying co-extensively with the base plate, end walls located at the ends of the mounting strip and having channel-shaped parts interposed between said mounting strip and the base plate and embracing the mounting strip, said parts being apertured to permit of the passage of the tongues through them, the mounting strip being also apertured to permit of the passage of the tongues through them, the tongues being bent over on the outside of the mounting strip, a spiral binding member, and means on the mounting strip for engagement with said spiral binding member.

2. A book binding comprising a plurality of 70 leaves bound together by a spiral, a pair of covers connected by a back strip, said back strip carrying a base plate, said base plate being formed with a plurality of spaced, struck-out tongues, a narrow, elongated mounting strip overlying the

base plate, the opposite ends of the mounting strip being inturned to form spiral-engaging hooks, an end member at each end of the mounting strip, each end member comprising a plate portion and an attached channel strip, at substantially right angles thereto said channel strip on each end member engaging one of the end portions of the mounting strip and having a part disposed between said mounting strip and the base plate, the mounting strip and channel strip portion of the end member having registered apertures through which one of the tongues extends, said tongue being bent over to thereby attach the mounting strip and the end member to the base plate, the spiral being engaged by the hooks at the opposite ends of the mounting strip.

3. A book binding comprising, a pair of covers connected by a back strip, said back strip having inner and outer layers, a curved base plate confined between said layers, said base plate having tongues projecting through the inner layer, a mounting strip extending longitudinally and centrally of the base plate on the inside of the back strip, the mounting strip having apertures through which the tongues extend, end members at the opposite ends of the mounting strip, said end members having disk-shaped walls and channel strips extending at right angles therefrom, said channel strips being apertured and being disposed between the mounting strip and the base plate, the tongues extending through the apertures in said channel strips, the tongues being bent over the face of the mounting strip to thereby attach the base plate, the mounting strip and the end members together, the opposite ends of the mounting strip being hooked for engagement with the convolutions of a spiral binding.

4. A book binding comprising a book having a back provided on its face with lining material, a curved base plate in the back behind said lining material, said curved plate having tongues extending from its concave side and penetrating the lining material, a mounting strip placed over the lining material and over the base plate behind the same, the mounting strip having apertures through which the tongues project, an end member at each end of the mounting strip, each end member comprising an upstanding substantially disk-shaped portion provided with a channel member extending from it, the channel member fitting on the end of the mounting strip and having a part located between the mounting strip and the lining material, said part having sides extending along the side edges of the mounting strip, said part having an aperture through which one of the tongues extends, the tongue being bent over on the face of the mounting strip to thereby unite the mounting strip, the end member and the base plate together, the mounting strip being provided with inturned hooks at its opposite ends for engagement with the convolutions of a spiral binder, and the mounting strip being provided with upstanding lugs for disposition between the convolutions of said spiral binder.
